METHOD OF MAKING TUBE

Raymond H. Hobrock, Troy Township, Oakland County, Mich., assignor to Bundy Tubing Company, Detroit, Mich., a corporation of Michigan

Application July 14, 1955, Serial No. 521,991

9 Claims. (Cl. 29—477.7)

This invention relates to the method of making tube from strip metal stock and it is directed particularly to the making of tube where the strip is moved lengthwise, fashioned into tubing with interfacial portions, and the interfaces united by a bonding metal which has been rendered molten.

Much tubing of this type has been made from strip steel stock wherein the interfaces are united by copper. The principal object of this invention is to provide a process for making tube from bare strip stock thus dispensing with the necessity of applying the bonding metal to the strip in the form of a coating or film. In accordance with the invention the bonding metal is introduced into the tube in the form of a strip or wire. The tube is subjected to a heat treatment to melt the bonding metal. The principal difficulty encountered is that tubing so fashioned and which is round in cross section twists on its axis. This is due apparently to different metal conditions as to relative hardness and softness and to various strains set up in the metal. As a result, the seam running lengthwise of the tube changes its position. When the strip or wire of bonding metal is rendered molten, it gravitates to the bottom of the tube, and if the seam is at the bottom of the tube, the bonding metal will flow between the interfaces to unite the interfaces upon solidification. However, if the tube twists so that in different longitudinal increments of the tube the seam is displaced upwardly from the bottom of the tube, the molten metal cannot flow in between the interfaces.

In accordance with this invention the tubing is made in an inverted manner so that the seam is normally positioned lowermost. And furthermore, the tube is fashioned into a non-circular form in cross section so that it can be guided and held in a position with the seam at the lower portion of the tube so that molten metal may flow in between the interfaces. Preferably, the tubing thus formed in an inverted manner is fashioned so that it is of elongate form in cross section with the long axis disposed substantially vertically and the short axis disposed substantially horizontally. After the bonding of the interfaces, the tubing is preferably subjected to a treatment to give it a substantially round or circular form in cross section.

The invention is disclosed in the accompanying drawings:

Fig. 1 is a general view indicating an apparatus as well as method for fashioning the tube in accordance with the invention with continuous lengthwise movement of the strip through a tube forming mill, a heating zone, a cooler, and a rounding unit.

Fig. 2 is a cross sectional view taken substantially on line 2—2 of Fig. 1 illustrating an early stage of the fashioning of the strip.

Fig. 3 is a cross sectional view taken substantially on line 3—3 of Fig. 1 showing final forming rolls.

Fig. 4 is a cross sectional view taken on line 4—4 of Fig. 1 showing the tube as formed.

2

Fig. 5 is a sectional view taken on line 5—5 of Fig. 1 illustrating the cooler.

Fig. 6 is a sectional view taken on line 6—6 of Fig. 1 illustrating sizing and rounding rolls.

Fig. 7 is a view illustrating a furnace through which a plurality of tubes may be passed for heating the same.

Fig. 8 is an enlarged sectional view taken substantially on line 8—8 of Fig. 7 illustrating a guide pipe in the furnace.

10 Referring first to Fig. 1, the strip 1 is drawn from a supply coil 2 and it is passed with lengthwise movement through a tube mill 4. The tube mill has forming rolls which fashion the strip transversely into hollow cross sectional form. The strip is formed about a mandrel 6 (Fig. 2), which is held by a bracket 8. This mandrel is hollow and a strip or wire 10 of bonding metal is drawn from a supply roll 11 and fed into the mandrel. In Fig. 2 an early stage of the formation of the strip is indicated as well also as the mandrel and the bonding metal within the hollow mandrel. The strip is preferably of steel and the bonding metal preferably of copper. However, other metals may be employed. For example, steel strip may be used with a bonding metal of solder, either hard or soft solder; the strip may be 20 Monel metal with an appropriate bonding metal.

The tube mill may be one of rather conventional form but the rolls are grooved to form the strip into elongate hollow cross sectional shape. The final rolls of the tube mill are shown at 15 and 16 and it will be 30 seen in Fig. 3 that the mandrel has an elongate cross sectional form and that the rolls 15 and 16 are grooved so as to form or wrap the metal of the strip with the elongate cross sectional form. The tube illustrated is one fashioned from a single strip of stock wherein the stock is rolled or fashioned through about 720° with the edges thereof bevelled or scarfed and fitted against an offset in the intermediate portion of the strip. The tube is generally illustrated at T in Fig. 4, the outside edge at 17 and the inside edge at 18. The inner and outer plies 40 of the tube are formed in tight interfacial engagement and the location where the edges 17 and 18 engage opposite sides of the intermediate part of the strip may be considered the seam. The interfaces between the body of the strip and the edge 18 intersect the inner surface of the tube. The tube thus formed can be guided and held so that the seam is held lowermost or, in other words, at the lower terminal of the long axis.

In Fig. 1 the strip and tube are moved continuously and as the tube emerges from the tube mill it enters a 50 heating zone. This may be in the form of a housing 20 into which a non-oxidizing or reducing gas may be entered through a pipe 21. This heating zone is of the electrical resistance variety. There are three roller electrodes 22, 23 and 24 with back up rolls 25, 26 and 27. 55 A transformer has a primary 33 connected to a suitable source of electrical current. One side of the secondary 28 is connected to the electrode roller 23 by a conductor 30. The other side of the secondary is connected to the electrode 22 by a conductor 31 and to the electrode 24 by a conductor 32. By connecting one side of the secondary to the two outside electrodes the problems of insulating the machine are minimized.

As the tubing moves through the heating zone it is 60 heated by electrical resistance to a temperature adequate for melting the bonded metal. The molten bonding metal gravitates to the bottom of the elongate tube and since the seam is held at the bottom the metal flows in between the interfaces. The molten metal will quickly traverse the entire interfacial area between the plies thus 65 flowing throughout the 360°. This is due to capillarity. The metal will not flow out from between the interfaces.

which intersect the outer surface of the tube at the edge 17 because the capillary space ceases at that point.

The tube leaves the heating zone and enters a cooler generally indicated at 35. This cooler is preferably of the jacketed type having an outer casing 36, and an inner casing 37, through which the tube travels. The inner tube or jacket 37 may be shaped, particularly for a portion of its length, to guide the tube and hold the seam down. However, after the bonding metal has solidified there is no further need of guiding the tube in the cooler but, of course, it is engaged and held positioned by the tools of the sizing and rounding unit. Cooling water may be passed between the jackets and may be introduced through a pipe 40 and discharged from pipe 41. The gas introduced through the pipe 21 may flow both upstream and downstream with some of the gas burning off at the inlet to the heating chamber and some discharging from the outlet end of the cooler.

With continuous movement the tube now passes through a sizing and rounding unit generally illustrated at 44. It comprises a series of suitably formed rolls which engage the tube and change its elongate cross sectional form into rounded form. The final rolls are indicated at 45 and 46 and the tube is given a circular or rounded form as indicated in Fig. 6. In the process just described, the strip moves successively through the forming mill, the heating zone, the cooler, and the rounding and sizing unit. The strip may move at fairly high speed because it can be rapidly heated by electrical resistance.

However, the method may be carried out by separating the heating unit and cooling unit from the tube mill and rounding unit. A suitable furnace is shown in Fig. 7 at 50 through which a plurality of tubes may be simultaneously passed. The tubes may be fed into the furnace by driving rollers 51 and 52. The furnace is suitably heated to raise the temperature of the tubes and melt the copper inside the same. As the tubes pass from the furnace they pass into cooler tubes 53 and when cooled to the point where they may be introduced to the atmosphere without objectionable oxidation they may pass out onto a support 54. The furnace may be supplied with a non-oxidizing or reducing gas through an inlet pipe 55 and this gas may escape from the inlet of the furnace and the outlet of the cooler.

The furnace is provided with a guide pipe for each tube. Such a guide pipe is shown in Fig. 8 at 56. It will be noted that the guide pipe is of elongate form in cross section to more or less fit the tube. In practicing the method of this invention with the furnace 50, the tube mill is separated from the furnace and tubes are formed rapidly thereby and cut into lengths. A plurality of the tubes are passed simultaneously through the furnace 50. The tubes pass through the furnace 50 much slower than they are made in the tube mill but by passing a plurality of tubes simultaneously through the furnace, the overall output of the furnace may substantially correspond to the output of the tube mill. After the tubes pass through the furnace and are cooled they may then be passed through the rounding and sizing unit 44 which, of course, in this instance, will not be necessarily in line with the tube mill.

In either case, the tube of elongate form in cross section can be held with facility so that the seam is maintained lowermost. Thus, when the wire or strip of bonding metal is rendered molten, it has access to the interfaces where the interfaces intersect the inside surface of the tube. When the system is used with the resistance heating zone, as shown in Fig. 1, the electrodes and the back up rollers serve to hold the tube in proper position. When the tubes are passed through the furnace 50 the respective guide pipes hold the tubes in proper position. It is not necessary to the invention that the seam in all increments of the tube remain accurately at the lower terminal of the long axis of the elongate form. It is

sufficient that the seam be held sufficiently near the lowermost portion of the tube or, in other words, near the lower terminal of the long axis to permit the molten copper to have access thereto and thus flow in between the interfaces. The terminology in the claims appended hereto are to be read with this interpretation.

I claim:

1. The method of making tube from strip metal stock comprising, moving the strip lengthwise, fashioning the strip into tubing of elongate form in cross section with the long axis disposed substantially vertically, bringing the edges of the strip into proximity with each other and with interfacing portions substantially at the lower terminal of the long axis, feeding a strip of bonding metal into the tube interior as it is being formed, passing the tube through a heating zone to melt the bonding metal, while utilizing the elongate form of the tube as a guide means for maintaining said edges substantially at the lower terminal part of the long axis, whereby the molten bonding metal, which gravitates to the lower portion of the elongate form, flows by capillarity between the interfaces, and cooling the tube to solidify the bonding metal and unite the interfaces.
2. The method of making tube from strip metal stock comprising, moving the strip lengthwise, fashioning the strip into tubing of elongate form in cross section with the long axis disposed substantially vertically, bringing the edges of the strip into proximity with each other and with interfacing portions substantially at the lower terminal of the long axis, feeding a strip of bonding metal into the tube interior as it is being formed, passing the tube through a heating zone to melt the bonding metal, while utilizing the elongate form of the tube as a guide means for maintaining said edges substantially at the lower terminal part of the long axis, whereby the molten bonding metal, which gravitates to the lower portion of the elongate form, flows by capillarity between the interfaces, cooling the tube to solidify the bonding metal and unite the interfaces, then treating the tube to change the elongate cross sectional form to a substantially round form.

3. The method of making tube with a double thickness wall from strip metal stock which comprises, moving the strip stock lengthwise, fashioning the strip into tubing of elongate form in cross section with the long axis disposed substantially vertically, and with inner and outer plies in interfacial relationship, bringing edge portions of the strip stock into proximity with each other substantial at the lower terminal of the long axis, feeding a strip of bonding metal into the tube interior as it is being formed, passing the tube through a heating zone to melt the bonding metal, while guiding the tube through the agency of its elongate form to maintain said edges substantially at the lower terminal of the long axis, whereby the molten bonding metal, which gravitates to the lower portion of the elongate form, flows by capillarity between the interfaces, cooling the tube to solidify the bonding metal and unite the interfaces, then treating the tube to change the elongate cross sectional form to a substantially round form.

4. The method of making tube with a double thickness wall from a single strip of metal stock which comprises, moving the strip lengthwise, fashioning the strip into tubing of elongate form in cross section with the long axis disposed substantially vertically, and with inner and outer plies in interfacial relationship, bringing the edges of the strip into proximity with each other on opposite sides of the intermediate part of the strip and substantially at the lower terminal of the long axis, feeding a strip of bonding metal into the tube interior as it is being formed, passing the tube through a heating zone to melt the bonding metal while utilizing the elongate form of the tube to guide the tube to maintain said edges substantially at the lower terminal of the long axis, whereby the molten bonding metal which gravitates

to the lower portion of the elongate form, flows by capillarity between the interfaces, cooling the tube to solidify the bonding metal and unite the interfaces, and then treating the tube to change the elongate cross sectional form to a substantially round form.

5. The method of making tube with a double thickness wall from a single strip of steel stock which comprises, moving the strip lengthwise, fashioning the strip into tubing of elongate form in cross section with the long axis disposed substantially vertically, and with inner and outer plies in interfacial relationship, bringing the edges of the strip into proximity with each other on opposite sides of the intermediate part of the strip and substantially at the lower terminal of the long axis, feeding a strip of copper into the tube interior as it is being formed, passing the tube through a heating zone to melt the copper while utilizing the elongate form of the tube to guide the tube to maintain said edges substantially at the lower terminal of the long axis, whereby the molten copper which gravitates to the lower portion of the elongate form, flows by capillarity between the interfaces, cooling the tube to solidify the copper and unite the interfaces, and then treating the tube to change the elongate cross sectional form to a substantially round form.

6. The method of making tube from strip metal stock comprising, moving the strip lengthwise, fashioning the strip into tubing of elongate form in cross section with the long axis disposed substantially vertically, bringing the edges of the strip into proximity with each other and with interfacing portions substantially at the lower terminal of the long axis, feeding a strip of bonding metal into the tube interior as it is being formed, passing the tube with continuous movement through a heating zone to melt the bonding metal, while maintaining said edges substantially at the lower terminal part of the long axis by utilizing the elongate form of the tube as a guide means, whereby the molten bonding metal, which gravitates to the lower portion of the elongate form, flows by capillarity between the interfaces, cooling the tube to solidify the bonding metal and unite the interfaces, then treating the tube to change the elongate cross sectional form to a substantially round form.

7. The method of making tube from strip metal stock which comprises, fashioning the strip into tubing of elongate form in cross section with the long axis disposed substantially vertically, bringing the edges of the strip into proximity with each other substantially at the lower terminal of the long axis to form interfacial portions, placing a strip of bonding metal into the tube interior, passing the tube through a heating zone to melt the bonding metal, while utilizing the elongate form of the tube

5 for guiding the tube to maintain said edges substantially at the lower terminal of the long axis, whereby the molten bonding metal, which gravitates to the lower portion of the elongate form, flows by capillarity between the interfaces, cooling the tube to solidify the bonding metal and unite the interfaces, and then treating the tube to change the elongate cross sectional form to a substantially round form.

10 8. The method of making tube from strip metal stock comprising, moving the strip lengthwise and fashioning it into tubing of acircular cross section with the strip edges in proximity with each other to form a seam area having interfaces generally at the lowermost portion of the tube, introducing a body of bonding metal into the tube interior as it is being formed and, while utilizing the acircular shape of the tube as a guide means to maintain said seam area generally at its lowermost portion, passing the tube through a heating zone to melt the bonding metal, so that the molten bonding metal gravitates 15 to the seam area and flows by capillarity between the interfaces, and cooling the tube to solidify the bonding metal and unite the interfaces.

20 9. The method of making tube from strip metal stock comprising, moving the strip lengthwise and fashioning it into tubing of acircular cross section with the strip edges in proximity with each other to form a seam area having interfaces generally at the lowermost portion of the tube, the slope of the portions of the tube wall adjacent said seam area being relatively greater 25 than that of the tube in its finished form, introducing a body of bonding metal into the tube interior as it is being formed, and, while utilizing the acircular shape of the tube as a guide means to maintain said seam area generally at its lowermost portion, passing the tube through a heating zone to melt the bonding metal, so that the molten bonding metal gravitates to the seam area and flows by capillarity between the interfaces, with said portions of the tube wall adjacent said seam area forming 30 a trough facilitating such flow to said seam area, cooling the tube to solidify the bonding metal and unite the interfaces, and treating the tube to decrease said slope of said wall portions and to change the acircular cross sectional form to a substantially round form.
